UNITED STATES PATENT OFFICE.

LOUIS HAUSMANN, OF NEW ORLEANS, LOUISIANA.

BUCKLE.

SPECIFICATION forming part of Letters Patent No. 417,420, dated December 17, 1889.

Application filed August 24, 1889. Serial No. 321,806. (No model.)

To all whom it may concern:

Be it known that I, LOUIS HAUSMANN, of New Orleans, in the parish of Orleans and State of Louisiana, have invented a new and Improved Suspender-Buckle, of which the following is a full, clear, and exact description.

My invention is an improvement in that class of suspender-buckles which consists of a plate having inwardly-bent perforated ears and a toothed gripper or jaw having trunnions adapted to enter the perforations. I provide the ears of such plate with openings and narrow open slots leading into them, and the gripper with headed trunnions adapted to pass through such slots and thereby enter the openings, whereby the plate and jaw may be quickly connected or disconnected.

Reference is to be had to the accompanying drawings, forming a part of this specification, in which similar letters of reference indicate corresponding parts in all the figures.

Figure 1 is a rear elevation of the improvement. Fig. 2 is a side elevation of the same on the line $x-x$ of Fig. 1. Fig. 3 is a plan view of the same. Fig. 4 is a face view of the blank for the front plate, and Fig. 5 is a face view of the blank for the gripping plate or jaw.

The improved buckle A is provided with a front plate B, on the lower end of which are held the suspender-ends C, of any approved construction. On the sides of the front plate B are formed rearwardly-extending U-shaped ears D, each of which is provided on its inner end D' with an opening D², into which is adapted to pass the trunnion E', formed on the gripping plate or jaw E, provided with the usual serrated edge adapted to engage the web of the suspender passed between the back of the front plate B and the said gripping-plate E. The gripping plate or jaw E is provided with the usual downwardly-extending arm E², adapted to be taken hold of by the operator to move said gripping plate or jaw up or down in order to engage the serrated edge with the web or disengage it from the same. On the outer end of each trunnion E' of the gripping plate or jaw E is

formed a head E³, located between the ends 50 of the U-shaped ear D and serving to prevent sidewise movement of the gripping plate or jaw E. In order to conveniently introduce the trunnions E' with their heads E³ into the respective ears D, a slot D³ is formed 55 at the end of each ear D, said slot leading from the outside into the opening D². The two prongs formed by the end of each ear D are pressed apart, so as to permit of introducing the trunnion E' into the respective 60 aperture D², after which the two prongs are again closed, and the trunnion is prevented from passing out of the aperture.

The blank from which the plate B is formed is shown in Fig. 4, and the blank from which 65 the gripping plate or jaw E is formed is illustrated in Fig. 5.

It will be seen that by thus constructing a buckle the pivotal parts are completely hidden, so that the buckle avoids sharp corners 70 or rough edges, which are usually liable to tear the shirt or other garment over which the suspender is used. It will further be seen that the gripping plate or jaw E is prevented from becoming detached from the 75 plate B on account of the heads E³ engaging the insides of the inner ends of the U-shaped ears D. Said heads E³ also prevent sidewise motion of the plate E, so that the latter always securely engages the web of the suspender with its serrated edge.

Having thus described my invention, what I claim as new, and desire to secure by Letters Patent, is—

In a suspender-buckle, the combination, 85 with a front plate provided with rearwardly-extending U-shaped ears having the openings D² and narrow open slots D³, leading to the same, of the toothed detachable gripper-jaw provided with lateral trunnions E', having heads E³ formed on their outer ends, said trunnions being adapted to pass through said slots, as shown and described, for the purpose specified.

LOUIS HAUSMANN.
